STRUCTURE FOR SEATING VACUUM CLEANER COVER

Axel Olof Engberg, Stockholm, Sweden, assignor to Aktiebolaget Electrolux, Stockholm, Sweden, a corporation of Sweden

Application December 10, 1953, Serial No. 397,385

Claims priority, application Sweden December 20, 1952

8 Claims. (Cl. 183—51)

My invention relates to vacuum cleaners of the type which employ a removable dust collecting member, and it is an object of the invention to provide an improvement to prevent seating of a cover at an access opening of such a cleaner unless a dust collecting member is positioned therein.

Operating a vacuum cleaner of this type, with the dust collecting member removed from the space in which it is normally positioned, is objectionable, because parts of the electric motor of the motor fan unit are exposed to dust and dirt which is entrained in air drawn into the interior of the cleaner. This often occurs when the dust collecting member is removed, as for cleaning or replacing with another member, for example, and the cover, which is removed to gain access to the dust collecting member, inadvertently is subsequently secured in position without first inserting a dust collecting member within the vacuum cleaner.

The above and other objects and advantages of my invention will become apparent as the following description proceeds, and the features of novelty which characterize the invention will be pointed out with particularity in the claims annexed to and forming a part of this specification.

For a better understanding of my invention, reference may be had to the following description taken in connection with the accompanying drawing in which:

Fig. 1 is a side view, partly in section, of a vacuum cleaner embodying my invention;

Fig. 2 is an enlarged fragmentary sectional view of part of the construction shown in Fig. 1;

Fig. 3 is a sectional view similar to Fig. 2 with the details of the dust collecting member omitted; and

Fig. 4 is a sectional view like that of Fig. 2 illustrating another embodiment of the invention.

Referring to Figs. 1 to 3 of the drawing, the vacuum cleaner which I have shown embodying my invention includes a casing 10 having a space 11 at one end thereof which receives a dust collecting member 12. The dust collecting member 12 comprises a filter bag 14 which may be formed of fabric or other suitable material permeable to air, and a part 15 of annular form which is fixed to the bag at the open end thereof. The part 15, which is essentially ring-shaped and serves as a reinforcement, is formed with an outwardly extending flange 16 to which is fixed a gasket 17 which may be formed of resilient material like rubber, for example.

A front cover 18 is provided for the casing 10 to close the access opening 19 of space 11 and also effectively hold the gasket 17 between the end of the casing and the cover, in a manner which will be described presently. Although not shown, the cover 18 and also a rear hood 20 may be fixed to the casing with any suitable fastening provisions.

The casing 10 is provided with a handle 21 and also a pair of runners 22 to facilitate movement thereof on a supporting surface. The cover 18 is formed with a central opening 23 to receive an end of a suction hose (not

2

shown) adapted to be removably secured to the opening in the cover in any suitable manner. Suitable cleaning appliances are connected to the outer free end of the suction hose through which air is drawn into the interior of the casing 10 by a motor fan unit (not shown) which may be positioned adjacent the filter bag 14.

During operation of the vacuum cleaner, air is drawn into the interior of the casing 10 through the opening 23 in the cover 18. Dust and dirt entrained in the air during a cleaning operation collect in the filter bag 14, and air free of such dust and dirt passes through the filter bag and flows through the casing and is eventually discharged by the motor fan unit through an end opening in the rear hood 20.

In accordance with my invention, I provide the cover 18 which is smaller than the access opening 19 into the space 11, so that the vacuum cleaner cannot be operated with the cover in its closed position until the dust collecting member 12 is properly positioned in the interior of the casing 10. In Figs. 1 to 3 the casing 10 is provided with an end ring 24 having an inwardly extending flange 25 which defines the access opening 19 into the space 11. The diameter of the cover 18 is smaller than that of the access opening 19 so that, when the dust collecting member 12 is removed from the space 11, the cover 18 can be moved through the access opening 19 into the space 11 of the casing 10 in the manner shown in Fig. 3.

However, when the dust collecting member 12 is inserted into the space 11 and properly positioned therein, the gasket 17 acts against the flange 25 which constitutes a shoulder or abutment at the open end of the casing 10 and serves to position the dust collecting member. Under these conditions the ring-shaped part 15, including the gasket 17 carried by the flange part 16 thereof, forms a seat for the cover 18, thereby rendering the latter effective to close the access opening 19 of the casing, as best shown in Fig. 2. With the cover 18 properly seated against the ring-shaped part 15 and also bearing resiliently against the gasket 17 carried thereby, the cover may be removably secured to the casing 10 with any suitable fastening provisions. By way of example and without limitation, the cover 18 may be removably secured to the casing by fastening means like that disclosed in Lundvall Patent No. 1,944,291.

The embodiment of Fig. 4 differs from the embodiment just described in that the part 15a of annular form, to which the filter bag 14a is secured, is provided with an outer rim portion 15b which is held between gaskets 17a and 17b held on the cover 18a and open end of the casing 10a, respectively. As shown in Fig. 4, the cover 18a and end ring 24a are formed to provide ring-shaped grooves which receive the gaskets 17a and 17b, respectively, which are desirably formed of a resilient material like rubber, for example.

The inner diameter of the gasket 17b is greater than the outer diameter of the gasket 17a, and the outer rim 15b of the ring-shaped part 15a, which is clamped between the gaskets 17a and 17b when the cover 18a is positioned to close the access opening 19a, slopes inwardly from the gasket on the casing 10a to the gasket on the cover 18a. When the dust collecting member 12a is removed from the space 11a, it will be evident that the cover 18a will pass through the access opening 19a and cannot be secured in position at the open end of the casing 10a.

In view of the foregoing, it will now be understood that in both of the embodiments illustrated and described above, the size and shape of the front end cover are so related to the size and shape of the access opening that, when the dust collecting member is removed from the space in which it is ordinarily positioned during normal operation of the vacuum cleaner, the cover cannot be

positioned on the casing to close the access opening. In accord with the invention, it is necessary to insert the dust collecting member into position in the interior of the casing at the access opening before the cover can be mounted on the casing to close the access opening, whereby the ring-shaped part or rim of the dust collecting member at the vicinity of the air inlet end thereof can provide a seat for the cover and maintain the latter in its closed position when the cover is removably secured to the casing in any well known manner.

Although I have illustrated and described particular embodiments of my invention, I do not desire to be limited to the particular arrangements set forth, and I intend in the following claims to cover all modifications which do not depart from the spirit and scope of my invention.

What is claimed is:

1. In a vacuum cleaner, a casing having an opening into the interior thereof and a cover for the opening, a dust collecting member through which air is adapted to pass, said dust collecting member normally being positioned in the interior of said casing within said cover, positioning means providing a seat for retaining said dust collecting member in its normal position, said cover being movable into the interior of said casing past said positioning means when said dust collecting member is withdrawn from said casing, and means including said dust collecting member, when the latter is seated on said positioning means, to provide a seat for holding said cover in position at the opening of said casing.

2. In a vacuum cleaner, a casing having an access opening, a dust collecting member having a rim part, said member being insertable into the interior of said casing at the access opening, positioning means providing a seat for retaining said rim part in position when said member is disposed in the interior of said casing, a cover for closing the opening, said cover being movable into the interior of said casing past said positioning means when said member is withdrawn from said casing, and means including said rim part, when the latter is seated on said positioning means, to provide a seat for holding said cover in position at the access opening of said casing.

3. Apparatus as set forth in claim 2 in which said means to provide a seat for said cover includes gasket means for said rim part, said positioning means including an abutment on said casing at which region said gasket means is retained in position when the access opening is closed by said cover.

4. Apparatus as set forth in claim 2 in which said cover

includes a first gasket and said positioning means includes a second gasket on said casing, said rim part being held between said gaskets when the access opening is closed by said cover.

5. Apparatus as set forth in claim 4 in which said rim part comprises an element extending about said member which serves as a reinforcement, said element being clamped between said gaskets when the access opening is closed by said cover.
- 10 6. Apparatus as set forth in claim 5 in which said gaskets are of annular form, the overall cross-sectional area of said gasket on said cover being smaller than the cross-sectional area of the opening defined by said gasket on said casing.
- 15 7. Apparatus as set forth in claim 6 in which said gaskets are ring-shaped with the outer diameter of said gasket on said cover being smaller than the inner diameter of said gasket on said casing, said element at said rim part being ring-shaped and sloping inwardly from said gasket on said casing to said gasket on said cover when said element is clamped therebetween.
- 20 8. In a vacuum cleaner, a casing having an opening into the interior thereof and a cover for the opening, a dust collecting member through which air is adapted to pass, said dust collecting member normally being positioned in the interior of said casing within said cover, positioning means providing a seat for retaining said dust collecting member in position, said cover being movable into the interior of said casing past the seat provided by said positioning means for said dust collecting member when the latter is withdrawn from said casing, and means including said dust collecting member, when the latter is seated on said positioning means, to provide a seat for holding said cover in position at the opening of said casing.
